TELEVISION APPARATUS

Fritz Schröter, Berlin, Germany, assignor to
 Telefunken Gesellschaft für Drahtlose Tele-
 graphie m. b. H., Berlin, Germany, a corpora-
 tion of Germany

Application January 5, 1932, Serial No. 584,788
 In Germany January 6, 1931

1 Claim. (Cl. 178—6)

The present invention relates to television receiving apparatus and is directed principally to a method and means by which the effective intensity and brilliance of the electro-optical image 5 constructed at the receiving point may be increased.

It is known in the prior art that the picture screen of a televiser receiver may be provided with a phosphorescent substance for the purpose 10 of converting or shifting the blue, violet and ultraviolet constituents of light radiation, which, while abundant in energy, are not very conspicuous in visual respect, into a physiologically brighter or more luminous spectral range, and 15 further of insuring a lower "blending or coalescence frequency" caused by the after-glow of the phosphorus. As will be seen upon closer examination, this latter aim is usually unattained in any system of the prior art, for when choosing a sort of phosphorus whose after-glow period 20 covers a period being longer than the building-up period of an individual television picture, blurred contours are produced in the reproduction of animated pictures. Whenever a rapidly decaying phosphorus is used no decrease in the physiologic flicker effect may be expected because of 25 the impairment of the cinematographic sector relation.

The principal purpose and object of the present invention thus is to utilize effectively the properties of phosphorus for securing a reduction 30 in flicker by the aid of a suitable process.

With this end in view there is used the property 35 of most grades or kinds of phosphorus first to store up energy by the action of primary irradiation or illumination, and then, subsequently, such stored-up energy may be released or given off by irradiation through the use of invisible rays. These invisible rays are principally 40 infra-red rays which act in a practically instantaneous manner in the shape of luminous emission, that is, the extinction so-called of phosphorus.

The invention will be understood best by referring 45 to the accompanying drawing which forms a part of this disclosure. In the drawing, Fig. 1 shows one form of the invention using a mirror-wheel as a scanning element; and Fig. 2 shows a modified form wherein a cathode ray image re-creating system is utilized.

To refer now to the form of the invention as 50 set forth by the mirror-wheel type of televiser of Fig. 1, it is seen that the light issuing from a luminous source 1 of constant intensity is focused by means of a condenser lens system 2

upon a Kerr cell and associated polarizing and analyzing Nicol prisms 3. The Kerr cell electrodes connect with the signal receiver so that the light from source 1 is modulated in the cell in accordance with the incoming picture impulses or signals and then is projected by the aid of an objective lens system 4 and a rotary mirror-wheel 5, or equivalent scanning element, upon the picture re-creation screen 6 upon which it is spread in a surface by virtue of the rotation of the mirror-wheel or scanning element. 5

The picture projection screen 6 is coated with phosphorous of a sort having the capability of accumulating luminous energy when irradiated with visible light, and of initially exhibiting 10 little after-glow. Among the grades of phosphorus of the said sort may be mentioned zinc sulfide comprising a heavy metal. 15

According to the present invention, after a suitable length of time, preferably after a period equalling in time that required to re-build half a picture a more or less suddenly occurring extinction of the picture points scanned or swept by the light rays re-creating the electro-optical picture by invisible radiation is produced, for instance, infra-red rays. For this purpose another mirror-wheel 7 is mounted upon the same spindle as the mirror-wheel 5, the former presenting a phase shifting angle 180 degrees with reference to the latter. The supplementary mirror-wheel 7 causes a ray of infra-red radiation issuing from a suitable radiation source 8 which is focused by an objective 9 upon the mirror-wheel 7 to scan the picture projection screen 6. In front of the radiation source 30 8, if desired, a suitable filter 10 could be mounted in the manner indicated. 35

What is evidently attained by an arrangement of the kind hereinbefore disclosed is that each picture point or unit during each rotation of the 40 mirror-wheel is rendered active twice or, in other words, the number of picture changes required to prevent the impression of a flicker is diminished or, to be more precise, about halved.

In case it should be found that in the selection 45 of a definite kind of phosphorus the extinction period inherent in the sweeping over the surface of the infra-red spot is too short, this condition may be remedied either by choosing the extintive infra-red spot substantially larger 50 than the picture re-creating visible spot or else by using a more or less wide infra-red light line or stripe for the purpose of extinction. The infra-red light line trails behind the motion of the picture re-creating luminous spot over the pic- 55

ture projection screen as above described. The width of this line, if required, may cover several picture lines.

From what has been above described, it will be seen that the requirements to be made of the precision and the optical qualities of the auxiliary mirror-wheel are very small indeed, so that a relatively crude and cheap form of construction will suffice.

10 The principle here described by the aid of a mirror-wheel television receiver may be readily applied also to picture scanning devices of different types such as has been suggested by the form of the invention shown by Fig. 2. This 15 embodiment is predicated upon the use of a Braun or cathode ray tube acting as the television receiver element, and the assumption has here been made that the infra-red extinction is insured, as above indicated, by the aid of a line 20 or stripe of infra-red radiation.

Similarly to the construction shown by Fig. 1, the cathode ray or Braun tube 12 may be connected with the receiver so that incoming signals control the ray intensity as shown, for example, 25 by U. S. Patent #1,470,696 through the use of grid control. The cathode ray 15 is suitably deflected by electrostatic or electro-magnetic fields 13 and 14 so as to cause the image points to be traced on the fluorescent end wall 15 of the tube 30 12.

After the electro-optical image has been formed on the end wall 15 of the tube 12, the infra rays from a source 17 may be caused to sweep over the picture screen by the agency of 35 a tilting or oscillating mirror 18 in a way readily understood from the drawing.

Care must be taken so that the motion of the tilting mirror 18 will be in synchronism with the period of the electron-ray motion inside the 40 Braun tube 12. This is accomplishable in a particularly simple manner if the deflector poten-

tials acting upon the cathode ray pencil are obtained from a tone-frequency generator equipped with rotating members as has been disclosed in U. S. patent application of August Karolus, Serial No. 545,965, filed June 22, 1931. The motion of the tilting mirror need then to be made dependent only upon the speed of rotation of the generator. It will be understood that in lieu of the said oscillatory mirror recourse may be had also to other similarly operating means for the 10 deflection of the radiations, such as a tilting prism or a mirror-studded drum.

Many modifications will suggest themselves and become apparent to those skilled in the art to which the invention relates and it is, therefore, 15 intended that the following claim shall be construed in the broad and generic sense to cover all such forms of the invention as would suggest themselves.

Having now described my invention, what I 20 claim and desire to secure by Letters Patent is the following:

In a television system, a cathode ray tube provided at one end with a phosphorescent screen, means for receiving signals representative of 25 fluctuating light intensities on successive elemental areas of a record surface, means for producing on said screen in accordance with said received signals sustained light spots of varying intensity representative of each elemental area 30 of a received picture, and an oscillatory means synchronized with the said light spot control means for traversing each elemental area of said screen at a time period substantially midway between the time period of recurrence of controlled 35 light illumination of each of said elemental screen areas by invisible light waves for extinguishing the fluorescent effect produced upon said screen by said initial illumination.

FRITZ SCHRÖTER.
